UNITED STATES PATENT OFFICE

HARRY ZIEGLER, OF SARATOGA SPRINGS, NEW YORK

HULL CONSTRUCTION

Application filed June 3, 1929. Serial No. 368,092.

This invention relates to a hull construction for boats, seaplanes and pontoons for marine craft.

The principal object of the invention is to provide a hull of the indicated character, embodying novel features of construction, whereby to decrease the wetted surface, or the wetted perimeter at any section thereof; to decrease the adhesion of hull and water; to obtain a material increase in speed by reducing skin resistance; to obtain a given speed with less power; to double the bottom of the hull and thus increase the safety factor thereof; to increase the strength without materially increasing the weight of the hull; and to decrease the take-off run in case of seaplanes and allow them to carry increased loads.

The invention will be best understood from a consideration of the following specification, taken in conjunction with the accompanying drawings, with the further understanding that the drawings illustrate only one example of the invention, and that the invention is not limited to any strict conformity with the showing in the drawings, but that the character of the material used and the details of the construction may be changed or modified within the spirit of the invention as expressed in the appended claims.

30 In the drawings:

Figure 1 is an outboard profile of a hull constructed in accordance with the invention.

Fig. 2 is a bow view.

35 Fig. 3 is an enlarged transverse sectional view taken on the line 3—3 of Fig. 1.

Fig. 4 is a central longitudinal section of the bow.

Referring now more particularly to the drawings, it will be apparent that for the sake of simplicity the hull of the present invention is one which is designed to be constructed entirely of metal, which will be of sufficient thickness so as to eliminate the necessity of ribs or other reinforcing members.

40 It is to be understood that the features of the invention may be incorporated in a hull whether for a boat or seaplane, or pontoon for marine craft. It is further to be understood 45 that the hull may be constructed of wood,

metal alloys, or combination of these materials as well as metal.

The hull, which as stated is made of metal, includes an inner bottom 10 and an outer bottom 11 joined to the sides 12. An air 55 passage or opening 13 is provided in the bow for the purpose of admitting air between the bottoms 10 and 11 in the forward movement of the hull. The outer bottom 11 is constructed to present overlapping portions which define a series of slots, slits or narrow openings 14 occurring transversely with respect to the longitudinal axis of the hull. The bottoms 10 and 11 are arcuate in cross section in the present instance. The 60 inner bottom 10 is arched or curved in an upward direction and joins the lower edges of the sides 12. The outer bottom 11 is constructed of overlapping portions, as stated, and each of these portions is arched or 65 curved in an upward direction from the keel of the hull at each side thereof to the junctions of the bottom 10 with the sides 12. This construction increases the safety factor and 70 also increases the strength of the hull without materially increasing its weight. The opening or passage 13 may be at the front, sides, top, or may branch to any combination of these places and lead between the bottoms 75 10 and 11. The opening or passage may be 80 of any size and of such dimensions as to meet sufficient on-coming air, so as to create a positive pressure between the two bottoms. If desired a fan or propeller may be operatively positioned in the opening to accomplish this result.

The slots 14 serve the purpose of discharging the water which has accumulated between the two bottoms, when the hull was at rest, and also for the purpose of discharging the 90 air entering the opening or passage 13, when the hull has attained sufficient acceleration, and water between said bottoms has been discharged.

The space between the bottoms will be 95 cleared of water by the acceleration of the hull, which will tend to shift or crowd the water to the rear, thus forcing it out through the slots 14. The air entering the opening or 100 passage 13 will be forced in between the two

bottoms, and thus create a positive pressure, and aid in forcing the water out through the slots. The water met by the outer bottom of the hull in the forward movement thereof will cause a suction action at the slots 14 and thus aid to draw the water out from between the bottoms. When the water that was between the bottoms is out, the air that is entering the opening or passage 18 will be 10 forced out and spread over the outer bottom, and thus decrease the wetted surface. Incidental to decreasing the wetted surface, there will be a decrease of adhesion of hull and water, thereby enabling a material increase 15 in speed by reducing the skin resistance, or the obtainment of a given speed with less power. It will also be apparent that the hull will have a double bottom construction of practical form which will increase the 20 safety factor and also increase the strength thereof without materially increasing the weight of the hull.

I claim:

1. A marine craft hull having an inner 25 and outer bottom defining a space closed at the sides extending longitudinally of the hull together with a series of rearwardly directed slots or openings in communication with said space, and provision to admit air at a forward 30 point above the water line into said space by the forward movement of said hull to be discharged through said slots or openings, for the purpose specified.

2. A marine craft hull having a passage 35 for entrapping air at a point above the waterline and for directing the air rearwardly of the bottom of the hull in the forward movement of the hull, and an outer bottom having overlapping portions defining rear- 40 wardly directed openings through which the entrapped air may flow.

3. A marine craft floatable hollow body having sides, and an inner and outer bottom, said outer bottom consisting of overlapping 45 sections joined to said sides of the body in spaced relation with respect to each other and said inner bottom, and said body having a passage for entrapping air at a point above the waterline of said body and for directing 50 the air rearwardly between said sections to decrease the adhesion of said body and water in the movement of the body in water.

4. A marine craft hull having an inner and outer bottom defining a space extending lon- 55 gitudinally of the hull, together with a series of rearwardly directed slots or openings in the outer bottom in communication with said space, and a passage extending rearwardly and downwardly of the hull for 60 admitting air at the bow above the waterline and directing it into said space by the forward movement of the hull to be discharged therefrom through said slots or openings, for the purposes specified.

5. A marine craft floatable body having an

inner bottom, and outer cross sectional upwardly arched bottom sections joining the inner bottom at the sides, and said outer bottom sections being arranged in spaced and overlapping relation with respect to each other.

HARRY ZIEGLER.
